UNITED STATES PATENT OFFICE.

REINHARD SCHEIDLER, OF NEWARK, OHIO.

VALVE-GEAR FOR STEAM-ENGINES.

SPECIFICATION forming part of Letters Patent No. 316,187, dated April 21, 1885.

Application filed June 11, 1884. (No model.)

To all whom it may concern:

Be it known that I, REINHARD SCHEIDLER, a citizen of the United States, residing at Newark, in the county of Licking and State of Ohio, have invented certain new and useful Improvements in Valve-Gear for Steam-Engines; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

My invention relates to improvements in steam-engines.

My invention relates to valve-gear for steam-engines; and it consists in certain improvements in the same, as described in the specification, and more particularly set forth in the claims.

A guide-bar for the valve is operated in a pair of guide-boxes, which latter are cast in a single piece with an oil-boat and bolted to one of the slides. A curved bracket bolted to the middle of the guide-bar, having the valve-rod and connecting-rod attached to its upper and lower ends, respectively, allows a more complete parallel as well as line movement, causing less wear of the operative parts, and adapting the engine for a greater amount of work with less cost for repairs than in the ordinary construction.

The object of the invention is to dispense with parts which are liable from wear to get out of order; also, to obtain a simple parallel line movement of parts connected with the valve and piston by the use of guides to each placed as nearly as possible in the same vertical plane and in the direct line of the stroke.

Figure 1 is a side elevation of a steam-engine having my improvements embodied therein. Fig. 2 is a top view of the same with the cover of the steam-chest removed. Fig. 3 is a view of the guide-bar and its connections. Fig. 4 is a vertical longitudinal section of the same with the bracket and valve-rod removed. Fig. 5 is an end view of the guide-bar with the bracket bolted thereto.

A is the steam-chest, which is shown in vertical longitudinal section in Fig. 1. In this engine it is placed on the top of the cylinder B. An ordinary slide-valve, C, is used.

The outer end of the valve-rod b extends through a guide, b'', on the outer end of the steam-chest, which resembles in its outward appearance that in common use in locomotives; but, unlike those, it has no stuffing-box. A hole of sufficient size for the valve-rod is bored through the piece b'' (which is cast solid) from the front end of the steam-chest, and is counterbored from the outside by a tool about double the size. The outer end of this larger hole is threaded and a steam-tight cap, b², screwed therein, and the space inside the latter babbitted. Two bearings are thus given to the valve-rod, and at the same time dispenses with a stuffing-box at this end of the latter.

On the outside top slide, i, and covering the entire upper surface of the same, is a flat plate, c², which is cast in a single piece with the upright square guide-boxes c thereon, and an oil-boat, o, between them. This plate has holes in its ends, and the bolts k, which secure the upper and lower slide-bars, i and i', together, extend through this plate also, securing it to the slide-bar i.

A square guide-bar, d, extends through the boxes c and operates therein, on which is bolted a bracket, C', bent to conform to the shape of bar d in the middle part, and curved at the top end to bring the latter in line with the valve-rod, which extends through it and is adjustably secured thereto by nuts n n on either side. The bracket C' is wide in the middle part, and is secured to the bar d by the horizontal bolts d' d' (Seen in Figs. 1 and 3.) Its lower end extends downward over the side of the slide i', and has a hole, g, therein for the wrist-pin e'' of the connecting-rod D.

The bracket C', being supported over the angle d' of the bar d upon the top and side of the latter, forms a very firm and strong connection between the valve-rod b and the connecting-rod D, and as the guide-bearings c of the bar d are cast in one piece with the plate c², and are wide apart, (being near the ends of the latter,) the whole gear operates smoothly and easily. In a rock-shaft connection the deflection of the end of the valve-rod by the oscillating arm causes the hole in the stuffing-box to wear vertically oblong, and sometimes knocking is caused by this or the wear of the valve carrier or bridle, both of which defects in the operation of the engine are avoided in

this construction. A hole, q , allows the oil in boat o to drop through, so as to lubricate the cross-head e^2 on that side of the engine-frame, thus utilizing a portion of the oil which 5 would otherwise be wasted.

Boxes c are provided with the usual means for taking up wear and for the adjustment of the guide-bar d .

The movement herein described can be used 10 with an eccentric instead of a crank connection by placing the guide-bar and bracket on the opposite slide i^2 and reversing the position of the bracket on the guide-bar.

I claim as my invention—

5 1. In a steam-engine, the combination of the valve-rod, the bracket connected therewith, the guide-bar to which the latter is attached, the plate having guide-boxes in which said guide-bar operates, the engine-slide on which 20 said plate is secured, and the connecting-rod pivotally connected to the lower end of said bracket, as and for the purpose set forth.

2. The combination, with the plate, guide-boxes, and guide-bar, of an oil-boat in said plate and means provided for allowing the 25 waste oil therein to lubricate the cross-head and slide beneath it.

3. In a valve-movement for steam-engines, the combination, with the valve-rod and connecting-rod, of a bracket connected at its upper and lower ends with said valve-rod and connecting-rod, respectively, and a guide-bar operating in guide-boxes attached to the slide of the engine, said bracket being reversible, whereby it may be operated with the valve-gear described by either a crank or eccentric connection, substantially as set forth. 30

In testimony whereof I affix my signature in presence of two witnesses.

REINHARD SCHEIDLER.
